UNITED STATES PATENT OFFICE.

NEWTON K. BOWMAN, OF NORTH LAWRENCE, OHIO, ASSIGNOR TO THE AMERICAN MINE DOOR COMPANY, A CORPORATION OF OHIO.

WALL-ANCHOR.

1,311,038.

Specification of Letters Patent. Patented July 22, 1919.

Application filed July 2, 1918. Serial No. 243,058.

To all whom it may concern:

Be it known that I, NEWTON K. BOWMAN, a citizen of the United States, residing at North Lawrence, in the county of Stark and 5 State of Ohio, have invented certain new and useful Improvements in Wall-Anchors, of which the following is a specification.

This invention relates to new and useful improvements in anchoring devices and 10 more particularly to a novel form of wall anchor especially designed for anchoring short wall mining machines in the tunnels of coal mines and the like.

It is common practice at the present time, 15 particularly in coal mines, to under cut the face or breast of a tunnel with a suitable mining machine and to then break the coal above down into the opening thus formed. To do this it is necessary that some means be 20 provided for holding the under cutting or mining machine against the breast of the wall. In many instances braces are placed against the rear of the machine and against the bottom of the tunnel but this is unsatisfactory as often times the floor of the tunnel 25 is of soft-clay which will let the braces sink and loosen the machine. In other instances expansion bolts or equivalent devices are driven into the wall above the part to be 30 under cut and a guy rope is extended from them to the rear of the machine. These expansion bolts, however, are of such a type that much labor and time must be consumed in freeing them from the wall after use.

35 Being familiar with the above conditions, one of the primary objects of the present invention resides in the provision of a wall anchor which may be readily inserted in a comparatively small hole drilled in the face 40 of the wall and quickly manipulated so that it may be locked in said wall, the construction of the anchor being such that it may be quickly operated so as to permit its ready release from the wall after use. A further 45 object of the invention is to provide a wall anchor including a shell having an expanding element slidably mounted therein and coacting with a pair of gripping dogs, means being provided at one end of the expanding 50 element for attachment to an anchoring cable so that after the dogs have been moved to gripping position by engagement with the expanding element the tension or stress of the anchoring cable on the expanding element will tend to actuate said expanding element to further force the dogs into the coal.

With these and other objects in view, my invention will be more fully described, illustrated in the accompanying drawings, and then specifically pointed out in the claims 60 which are attached to and form a part of this application.

In the drawings:

Figure 1 is a top plan view partly in section showing the improved anchor embedded 65 in the breast of a tunnel and in operative position with respect to a short wall mining machine;

Fig. 2 is a longitudinal sectional view showing the position of the various parts 70 comprising the wall anchor after said anchor has been inserted in the breast of a tunnel and before the expanding element has been actuated to operate the gripping dogs;

Fig. 3 is a similar view showing the dogs 75 moved to operative position by the expanding element;

Fig. 4 is a similar view showing the position of the several parts after the anchoring cable has been placed under tension; 80

Fig. 5 is a perspective view of the wall anchor detached;

Fig. 6 is a perspective view of the different parts comprising the wall anchor detached; 85

Fig. 7 is a transverse sectional view taken on the line 7—7 of Fig. 2;

Fig. 8 is a similar view taken on the line 8—8 of Fig. 3.

The improved device forming the subject-matter of the present invention is principally designed for anchoring mining machines in the tunnels of coal mines and in Fig. 1 of the drawings the anchor is shown embedded in the breast 5 of a tunnel and 90 operatively connected through the medium of a cable 6 with a short wall mining machine, indicated at 7.

The device comprises a cylindrical shell or casing 8 having its outer end provided with 100 oppositely disposed stop lugs 9, the terminals of which are bent inwardly, as indicated at 10, and adapted to be embedded in the face of the tunnel, as shown. Slidably mounted within the casing is an operating 105 member or rod 11 having its inner end provided with a reduced shank 12, the exterior walls of which are threaded for engagement with the correspondingly threaded walls of a socket 13 formed in the cylindrical body 110 portion 14 of an expanding element 15. The outer end of the rod 11 is provided with an

annular stop shoulder 16 and a terminal hook 17 adapted to receive one end of a cable 6 whereby the cable may be detachably secured to the wall anchor. The free end of 5 the expanding element 15 projects longitudinally beyond the adjacent end of the casing 8 and the upper and lower faces of said expanding element are provided with grooves 18 in which are seated gripping dogs 10 or shoes 19, the grooves 18 are dovetailed in cross section while the gripping dogs 19 are correspondingly dovetailed, as best shown in Fig. 7 of the drawings, so as to prevent accidental displacement of the gripping dogs, 15 while at the same time allowing said dogs to be moved longitudinally with respect to the expanding element. The bottom walls of the grooves 18 are inclined toward the center of the expanding element so as to 20 form a wedge-shaped terminal and thus force the gripping dogs outwardly into engagement with the coal when the expanding element is adjusted longitudinally within the casing. The gripping dogs 19 are preferably provided with one or more transverse teeth 20 adapted to bite into the coal and prevent accidental displacement of the anchor when tension is exerted on the cable 6. The inner ends of the dogs 19 are 25 provided with longitudinally extending ears 21 having threaded openings 22 formed therein and adapted to receive correspondingly threaded screws 23. The heads of the screws 23 pass loosely through correspondingly 30 shaped openings 24 formed in the casing 8 and serve to anchor the gripping dogs with respect to the casing, while at the same time permitting said dogs to expand and contract laterally according to the position of the 35 expanding element. The grooves 18 are preferably disposed in longitudinal alignment with the lugs 10, although if desired, said grooves may be arranged at right angles thereto and any desired number of grooves 40 and anchoring dogs may be employed as may be found desirable or necessary to the proper operation of the anchor.

In use a hole of suitable dimensions, usually two inches in diameter and about 50 fifteen inches deep, is drilled in the breast 5 of the tunnel and the anchor with the parts in the position shown in Fig. 2 is inserted in this hole, after which the actuating member or rod 11 is rotated so as to 55 draw the expanding element longitudinally of the casing and force the gripping dogs laterally into engagement with the coal, as best shown in Fig. 3 of the drawings. The anchoring cable 6 is then attached to the 60 hook 17 and the winch or drum 23 of the mining machine rotated so as to place the cable 6 under tension, the tension of the cable 6 serving to move the rod 11 to the position shown in Fig. 4 of the drawings 65 and in so doing forces the gripping shoes 19

with greater pressure against the coal. It will thus be seen that the greater the pull on the hook 17 the tighter the dogs will grip the coal so as to effectually prevent accidental displacement of the anchoring 70 member. In order to release the anchoring member, the cable 6 is detached from the hook 17 and the rod 11 rotated in the reverse direction which retracts the gripping dogs 19, after which a pick or other suitable 75 tool is inserted behind the lugs 9 and a longitudinal pull exerted thereon which permits the casing and its associated parts to be readily removed from the hole in the wall of the tunnel. It will here be noted that 80 owing to the dovetailed formation of the grooves 18, the gripping dogs will be forced outwardly or inwardly according to the direction of movement of the expanding element, the parts being so arranged that the 85 greater the pull on the expanding element the tighter the dogs will bite into the coal.

While the anchor is principally designed for use in connection with mining machinery, it will, of course, be understood that 90 said device may be employed for any purpose for which it may be found desirable or applicable without departing from the spirit of the invention.

Having thus described my invention, what 95 is claimed as new is:

1. A wall anchor including a casing, an expanding element slidably mounted within the casing and provided with oppositely disposed grooves the walls of which are inclined, gripping dogs normally seated in and bearing against the inclined walls of said grooves and each having its inner end provided with a pin and slot connection with the casing, and an actuating member 100 having its inner end operatively connected with the expanding element and its outer end provided with means for engagement with a cable, said actuating member when rotated serving to move the dogs to gripping 105 position.

2. A wall anchor including a casing having one end thereof provided with laterally extending lugs and its other end formed with oppositely disposed openings, an expanding element slidably mounted within the casing and provided with longitudinal grooves, the bottom walls of which are inclined, gripping dogs slidably mounted in the grooves and provided with ears, fastening devices loosely passing through the openings in the casing and secured to the ears of the gripping dogs, and a rod, one end of which is provided with means for attachment to a cable and its other end connected with the expanding element.

3. A wall anchor including a casing having one end thereof provided with oppositely disposed openings, an expanding element slidably mounted within the casing 130

- and having its outer end projecting longitudinally beyond the casing and formed with grooves dovetailed in cross-section and provided with inclined bottom walls, gripping dogs slidably mounted on the inclined bottom walls of said grooves and provided with ears, fastening devices passing loosely through the openings in the casing and engaging the ears, and a rod having one end 10 thereof provided with a hook and its other end connected with the expanding element.
4. A wall anchor including a casing, an expanding element slidably mounted within the casing and having its outer end provided 15 with a wedge-shaped portion and its inner end formed with a threaded socket, gripping dogs bearing against the wedge-shaped portion of the expanding element, a connection between the gripping dogs and the casing,
- 20 a rod mounted for rotation within the casing and having its inner end provided with a threaded shank engaging the threads of the socket, the outer end of the rod being provided with a shoulder adapted to bear against the adjacent end of the casing and having a terminal hook adjacent said shoulder for engagement with an anchoring cable.
5. A wall anchor including a casing, an 25 expanding element disposed within the casing and provided with a seating groove having an inclined wall, a gripping dog seated in said groove and normally bearing against the inclined wall thereof and having its inner end provided with a pin and slot connection with the casing, an actuating member mounted for rotation within the casing for moving the dog to gripping position, and means carried by the actuating member 30 for engagement with a cable, the tension

of the cable serving to partially withdraw the actuating member from the casing and further expand the gripping dog.

6. An anchoring device including a casing, an expanding element disposed within the casing and including a wedge-shaped portion, gripping dogs bearing against the wedge-shaped portion of the expanding element and operatively connected with the casing, an actuating member operatively connected with the expanding element and rotatable within the casing for moving the dogs to gripping position, a cable secured to the actuating member, and means for placing the cable under tension whereby to exert 45 a longitudinal pull on the actuating member and impart an additional outward force 50 to the gripping dogs.

7. A wall anchor including a casing, an expanding element slidably mounted within the casing and including a wedge-shaped portion, and gripping dogs engaging the wedge-shaped portion of the expanding element and operatively connected with the casing whereby longitudinal movement of 55 the expanding element within the casing will force the dogs laterally in a straight line to gripping position.

8. A wall anchor including a casing, an expanding element slidably mounted within the casing provided with oppositely disposed grooves the walls of which are inclined, and gripping dogs bearing against the inclined walls of said grooves and having their inner ends operatively connected with the casing 70 whereby longitudinal movement of the expanding element will force the dogs laterally in a straight line to gripping position.

In testimony whereof I affix my signature.
NEWTON K. BOWMAN. [L. s.]
